UNITED STATES PATENT OFFICE.

CHARLES G. PALMER, OF NEWARK, NEW JERSEY.

ROD CONNECTOR.

Application filed January 23, 1922. Serial No. 531,063.

To all whom it may concern:

Be it known that I, CHARLES G. PALMER, a citizen of the United States, residing in Newark, in the county of Essex and State 5 of New Jersey, have invented certain new and useful Improvements in Rod Connectors, of which the following is a specification.

The object of the invention is to provide means for connecting the ends of rods with 10 other mechanical elements in such manner as to admit of relative adjustment and firm clamping when the desired adjustment has been made.

Another object is to afford means whereby 15 the engaged element is pivotally secured to the connector, the pivot having means by which it may be manually retracted, or held in operative position by other means formed with the connector.

20 A further aim is to provide a simple connector, of the type described, capable of being made from a single blank of sheet metal or a casting as preferred.

These purposes are attained by the novel 25 design and construction of parts, hereinafter described and shown in the accompanying drawing, forming an essential part of the disclosure, and in which:—

Figure 1 is a fragmentary sectional view 30 showing the application of the connector to a door latch operating device.

Figure 2 is a front elevational view of the connector as engaged with associated parts.

35 Figure 3 is a side view of the device in detail.

Figure 4 is an end view of the same.

Figure 5 is a rear elevational view showing a modified form of construction.

40 Figure 6 is a plan view of the blank from which the preferred form of the connector is made.

In the adaption shown the connector is indicated as engaging between the slidable 45 rods or bars of a door latch bolt, of the type known as panic bolt, in which it may become necessary to instantly release it in order that the door can be opened hurriedly, as in the case of fire or like emergency.

50 In installing such devices difficulty is often encountered in obtaining the exact length of the operating rods, which obviously must be accurate in order that the device function properly, and to avoid such trouble has been the main purpose of the invention.

However, it will be apparent that a wide variety of other like mechanisms may be satisfactorily served by the device.

In Figure 1 the numeral 10 designates the 60 frame or jamb of the door 11, to the inner side of which are engaged brackets 12 and 13 respectively near its top and midway in its length.

A keeper 14, fixed in the jamb, is adapted 65 to receive a latch bolt 15 slidable in the bracket 12, through which extends the bolt shank 16, secured to a rod 17 by a connector 18 and operatively engaged in the bracket 13 by the actuating lever handle 19. 70

The preferred form of the connector is made from a sheet metal blank, shown in detail in Figure 6, consisting of an elongated body having between its sides 20 and 21 a slot 22. At each end 23 and 24 are pairs 75 of perforations 25—25' and 26—26', the corners being rounded as shown.

Arms 27 and 28 extend outwardly from the side element 20, these arms having curved outer ends and containing perforations 29 and 30 respectively. 80

Extending out from the arm 28, are opposed lugs 31 adapted to be bent on the lines 32 to stand substantially parallel.

The ends 23—24 are sharply bent on lines 85 registering with the ends of the slot 22 and the sides 20—21 are formed to present circular bands from which the elements 23—24 extend parallel and closely adjacent to each other (see Figures 2 and 4) the bands being 90 fitted to a rod or bar, as the element 17, and tightly clamped therearound by bolts or screws 33, passed through the perforations 25 and 26 and provided with nuts 34.

The arms 27 and 28 are offset, curved and 95 bent to constitute forks engageable with the element 16 and held thereto by a pin 35 passing through the perforations 29—30 and a corresponding hole in the element 16.

One of the ends of the pin 35 is bent 100 at a right angle 36, turned to extend between the lugs 31, which project outwardly beyond the element 36, and when bent inwardly toward each other, as shown in Figure 4, maintain the pin securely but 105 movably in position.

While the foregoing applies more particularly to a sheet metal connector, it will be understood that the same may be cast or drop forged to present like elements 110 without material change in structure.

In the modification, shown in Figure 5,

the same general characteristics are observable, the lugs 31 however being omitted and the pin 35 fixedly engaged in the element 16, the arms, when the bolts are relaxed, 5 being sufficiently elastic to spring out and allow the pin to enter the perforations, whereupon the clamp screws secure the device in position.

From the foregoing it will be seen that an 10 extremely simple one piece connector has been disclosed, readily adjustable on the element 17 so that the latter can be moved relative to the element 16 and then rigidly clamped, the element 16 pivoting on the pin 15 35 if such action is desirable.

While certain preferred embodiments of this device have been shown and described, it will be understood that changes in the 20 form, arrangements, proportions, sizes and details thereof may be made without departing from the scope of the invention, as defined in the appended claims.

Having thus described my invention, what 25 I claim as new and desire to secure by Letters Patent, is:-

1. A device of the class described comprising a band having spaced ends, means for contracting said band, opposed arms extending from one edge of said band, and means 30 passing through said arms for removably engaging an article with said band.

2. A device of the class described comprising a pair of bands having out-turned flanged ends connected between the bands, 35 arms formed on opposite sides of one of said bands, said arms being perforated in register, all of said elements being integral, a pin engaging in the openings of said arms, and clamp bolts operatively engaging the 40 flanged ends of said bands.

3. A device of the class described comprising one or more bands, means for contracting said bands, off-set arms extending in opposed relation from one of the bands equidistant and parallel with the axis of the 45 band, a pin fitting holes in said arms, said pin being positioned diametrically across the opening in the band, and an angular extension on said pin whereby it may be manipulated.

4. A device of the class described comprising a pair of spaced bands integrally united at their flanged ends, bolts adapted to clamp said ends, a pair of arms extending from opposite sides of one of said bands, 50 a pin passing through said arms, and means for maintaining said pin when assembled.

5. A device of the class described comprising a pair of spaced bands suited to encircle an object, flanges extending in parallel from the ends of said bands, integral connections between said pairs of flanges, clamp bolts passing through each pair of flanges, arms extending from the opposite side edges of one of said bands, a 55 pin engageable in openings near the ends of said bands, a pin engageable in openings near the ends of said arms, and an angular extension formed with one end of said pin, a pair of opposed lugs extending laterally from one 60 of said arms, said lugs being engageable with said angular element whereby the pin is held confined in said arms.

This specification signed and witnessed this 21st day of January, 1922.

CHARLES G. PALMER.
